United States Patent Office

Des. 176,060
Patented Nov. 15, 1955

176,060

SHOE

William E. Bolding, Newark, N. J., assignor to Johnston & Murphy, Newark, N. J., a corporation of New Jersey

Application April 27, 1955, Serial No. 35,694

Term of patent 7 years

(Cl. D7—7)

FIG. 1.

FIG. 2.

FIG. 3.

Fig. 1 is a view in top plan of a shoe showing my new design.

Fig. 2 is a view in elevation of the outer side of the shoe of Fig. 1.

Fig. 3 is a view in elevation of the inner side of the shoe of Fig. 1.

The dominant features of the design reside in the portions thereof shown in the accompanying drawings in full lines.

I claim:

The ornamental design for a shoe, as shown and described.
